UNITED STATES PATENT OFFICE.

CHARLES W. TROWBRIDGE, OF CHICAGO, ILLINOIS.

SAWING-MACHINE.

SPECIFICATION forming part of Letters Patent No. 390,628, dated October 2, 1888.

Application filed June 26, 1888, Serial No. 273,287. (No model.)

To all whom it may concern:

Be it known that I, CHARLES W. TROWBRIDGE, residing at Chicago, in the county of Cook and State of Illinois, and a citizen of the 5 United States, have invented a new and useful Improvement in Portable Metal-Sawing Machines, of which the following is a specification, reference being had to the accompanying drawings, in which—

Figure 1 is a front elevation. Fig. 2 is a section at line 2 of Fig. 1. Fig. 3 is a section at line 3 of Fig. 1. Fig. 4 is a side elevation. Fig. 5 is a perspective. Fig. 6 is a perspective showing a modification.

In Figs. 1, 2, 3, and 4 the device is supposed to be attached to an I-beam turned over upon its side, the beam being small.

In Fig. 5 the device is shown attached to a beam standing in a vertical position, the beam 20 being larger than that shown in Fig. 4.

In Fig. 6 the device is shown attached to the under side of a rail.

My invention relates to portable metal-sawing machines.

The invention consists in providing a stationary frame adapted to be fastened to the material which is to be cut, on which stationary frame a secondary frame moves when the machine is in use, carrying a circular saw 30 which does the cutting, and in providing automatic feeding devices.

That which I claim as new will be pointed out in the claims.

In the drawings, A represents the main frame 35 or plate provided with a fixed jaw, a.

B is a movable jaw connected with a screw, C. There is a screw-thread in the part b to receive the screw C. A pin, d, projects from the jaw B, which pin passes through a slot in 40 the frame A.

e is a nut on the pin d. This nut is located in a groove, f, in the plate or frame A.

D is a frame arranged to slide upon the frame A.

45 E is a saw mounted on a shaft, F.

G is a shaft provided with a screw-thread which engages with a worm-pinion, g, upon a screw-threaded shaft, H, which is supported in suitable bearings, h.

50 i is a housing over the pinion g.

j is a beveled wheel on the inner end of the shaft G, which engages with another beveled gear-wheel, k, on the shaft I, which is supported in a suitable bearing.

l is a pinion on the shaft I.

m is a gear-wheel on the shaft F, which carries the saw.

The bearings for the shafts F G I and the 60 housings for the wheels j k l m are cast with the sliding frame D.

n is a covering-plate.

o in Fig. 1 is a pin which passes through a crank-arm, p, which is secured to a screw-shaft, H, the pin being designed to prevent the crank from rotating.

J is a lever which passes through the upper 65 end of a socket, q, adapted to engage with the square end r of the shaft G.

When the power is available the machine can be run by means of flexible shafting connected to the shaft G at r.

The machine is adapted to be used in cutting I-beams, railroad-rails, channel-irons, angle-irons, T-irons, and other irons.

In Fig. 6 I have shown a modification, the 70 device there shown being adapted to be attached to the under side of a railroad-rail, and in this figure I have shown two operating-levers. Other modifications will readily occur to a mechanic skilled in the art which may be 75 necessary to adapt the device to be secured to different forms of beams or rails.

I do not limit myself to the precise arrangement of operating devices which I have shown.

The operation is as follows: The device is to 80 be secured to the metal upon which the saw is to operate by means of the jaws a and B, as indicated in Figs. 4 and 5. Then by means of the lever J the shaft G is to be rotated, and motion will thereby be given through the 85 wheels j k l m to the saw, and at the same time through the screw-thread on the shaft G and worm-pinion g the frame D will be moved, sliding upon the frame A, carrying the saw forward. When the cutting operation has 90 been performed, the pin o is to be removed and the screw-shaft H can be rotated, bringing the frame D and the parts thereon back to the proper position to be again used.

The frame A not only supports the frame D, 95

but also serves the purpose of a guide for it.

That which I claim as new, and desire to secure by Letters Patent, is as follows:

1. In a portable metal-sawing machine, a main frame and guide, A, adapted to be secured to and supported by the material to be cut, in combination with a sliding frame, D, a shaft, F, supported in bearings upon the sliding frame D, and a circular saw, C, mounted on said shaft F, substantially as and for the purpose specified.

2. A portable main frame and guide, A,

adapted to be secured to and supported by the material to be cut, and a sliding frame, D, and circular saw upon a shaft supported by the frame D, in combination with automatically-operating devices for feeding the saw while cutting, consisting of a screw-threaded shaft, C, worm-gear g , and screw-threaded shaft H, substantially as and for the purpose specified. 20

CHARLES W. TROWBRIDGE.
